SHOE POLISHER

Albert J. Dremel and Robert E. Dremel, Racine, Wis.,
assignors to Dremel Manufacturing Co., Racine, Wis.,
a corporation of Wisconsin

Filed July 19, 1961, Ser. No. 65,985

Term of patent 14 years

(Cl. D9—2)

FIG. 1 is a side perspective view of a shoe polisher showing our new design. The side opposite is a mirror image of the side shown.

FIG. 2 is an enlarged rear elevational view thereof. The dominant features of our design reside in the portions shown in full lines.

We claim:

The ornamental design for a shoe polisher, substantially as shown and described.
